UNITED STATES PATENT OFFICE.

WOODSON T. MERCHANT, OF LOUISVILLE, KENTUCKY.

HOSPITAL-BED.

1,038,623.

Specification of Letters Patent. Patented Sept. 17, 1912.

Application filed August 14, 1911. Serial No. 644,026.

To all whom it may concern:

Be it known that I, Woodson T. MERCHANT, a citizen of the United States, residing at Louisville, in the county of Jefferson 5 and State of Kentucky, have invented certain new and useful Improvements in Hospital-Beds, of which the following is a specification.

This invention relates to improvements 10 in beds of the kind generally known as hospital or invalid beds, and it comprises suitable supporting posts, a mattress - frame thereon composed of two sections, one of which extends beyond and is secured to the 15 foot posts, the sections being hinged together at one of the foot posts, so that the foot section and the other foot post may be swung to one side of the main section to permit the physician or attendant to stand in 20 the space normally occupied by the foot section of the mattress.

The mattress is made in two sections, the lower or foot section being movable onto the extended foot section of the bed so as to 25 break the mattress in the middle and permit the use of a commode without swinging the foot section of the bed frame to one side, and also in order that the foot section of the bed frame may support the foot section of 30 the mattress when the former is swung away from normal position.

The invention also comprises an adjustably supported commode, or douche pan arranged at the center of the bed, which may 35 be moved upward for use when the mattress sections are moved apart and may be moved downward beneath the mattress when not in use.

In the accompanying drawing,—Figure 1 40 is a side elevation of the invalid bed embodying my invention, the parts being shown in normal positions in full lines; Fig. 2 is a side view, partly in section, of the commode or douche pan; Fig. 3 is a top plan 45 view of the same; Fig. 4 is a section on the line 4—4 of Fig. 1; Fig. 5 is a detail view showing the hinge in one side of the bed frame; Fig. 6 is a horizontal section through the joint in the opposite side of the frame; 50 Fig. 7 is a top plan view of the bed with the foot section of the bed swung out.

Referring to the drawing, 1 and 2 indicate the head posts and 3 and 4 the foot posts of the bed, upon which is mounted a 55 rectangular supporting frame for the mattress comprising sections *a* and *b*, which are

hinged together and adapted to swing about the post 3 as an axis, relatively to one another. The section *a* comprises side pieces 5 and 6 of angle iron, both connected rigidly 60 to the head posts and also connected by suitable cross pieces, one of which is indicated at 7. The side piece 5 extends from the head post 1 to the foot post 3 and is provided with an eye 8 which is journaled upon said 65 foot post. The side piece 6 extends from the head post 2 to a point adjacent the foot post 4. The section *b* comprises side pieces 9 and 10 which are rigidly secured to the foot posts 3 and 4 and extend beyond the same, 70 these side pieces being connected by an end piece 11. The side piece 6 is provided with an eye 12 adapted to receive a projection 13 on the side piece 10 and a bolt 14 and clamping nut 15 normally connect the side 75 pieces 6 and 10 of the two sections so as to form a rectangular frame which extends beyond the foot post. A brace 16 extends between the side piece 5 and a sleeve 16^a on the post 3. The mattress is composed of two 80 sections 17 and 18, adapted to rest upon the frame between the head and foot posts. The foot section 18 may be moved from the position shown in full lines in Fig. 1 to the position shown in dotted lines, while the two 85 parts of the bed frame are in normal position, thus separating the mattress so as to permit of the use of the commode C arranged beneath the mattress.

For obstetrical purposes the section 18 of 90 the mattress may be moved onto the section *b* of the bed frame and said latter section may then be unlocked at the joint between the side bars 10 and 6 and swung outwardly 95 at any desired angle to the section *a*, thus permitting the surgeon or nurse to step in between the sides 5 and 6 of the frame to attend the patient. Before unlocking the bed frame an adjustable leg 19, hinged at 20 to the side bar 6, is let down, as indicated at 100 dotted lines in Fig. 1, to support the side bar, and when the frame is unlocked the section *b* is swung outwardly and an adjustable leg 21, pivoted to the end piece 11, is 105 let down to support the section *b*. The section *a* will then be supported upon the legs 1, 2, 3 and 19 and the section *b* will be supported upon the legs 3, 4 and 21. Stirrups 22 and 23 are suitably supported upon the sides of the bed frame for use by the patient 110 when necessary.

In bearings 24, secured to the cross piece

7, are arranged rods 25 which extend lengthwise of the bed and are adjustably secured by thumb screws 26. These rods support the commode C. The latter comprises a 5 receptacle 27 having guideways 28 on its sides in which are arranged slides 29. The rods 25 extend through suitable openings in the slides and set screws 30 are provided for securing the rods to the slides. Set 10 screws 31 are also provided for clamping the slides to the guideways so that the receptacle 27 may be held at different elevations with respect to the mattress. This receptacle is shown with an inner vessel 32 15 and an adjustable cover 33 which may be removed downward to close the vessel 32 or may be removed from the receptacle if desired. An apron 34, hinged to one side of the receptacle 27, may be turned over upon 20 the mattress as shown in Fig. 2, to prevent the mattress from being soiled, or this apron may be swung inward when it is desired to lower the commode. It will be evident that by loosening the set screws 31 the 25 commode may be lowered to a position below the mattress, as shown in Fig. 1, or it may be adjusted into position for use, as shown in Fig. 2.

What I claim is:

- 30 1. An invalid bed comprising head and foot posts and a frame connecting said posts and extending beyond the foot posts, said frame comprising two sections having their side bars, at one side of the bed, hinged together, and their side bars, at the other side of the bed, detachably connected together. 35
2. An invalid bed comprising head and foot posts and a frame connecting said posts and extending beyond the foot posts, 40 said frame comprising two sections one fixed to the head posts, the other fixed to

the foot posts, the side bars of said sections, at one side of the bed, being hinged together at one foot post, and the side bars of said sections, at the other side of the bed, 45 being detachably connected together at a point between the head and foot posts.

3. An invalid bed comprising head and foot posts and a frame connecting said posts and extending beyond the foot posts, said 50 frame comprising two sections one fixed to the head posts, the other fixed to the foot posts, the side bars of said sections, at one side of the bed, being hinged together at one foot post, and the side bars of said sections, 55 at the other side of the bed, being detachably connected together at a point between the head and foot posts, and folding legs for supporting said sections when the latter side bars are disconnected.

4. An invalid bed, comprising head and foot posts, and a frame connecting said posts and extending beyond the foot posts, said frame comprising two sections, one section fixed to the head posts, the other section fixed to the foot posts, the side bars of said sections, at one side of the bed, being hinged together at one foot post and the side bars of said sections, at the other side of the bed, being detachably connected together, 65 in combination with a two-part mattress normally extending between the head and foot posts, one part of said mattress adapted to slide on the bed frame from one section of the latter to the other. 70

In testimony whereof I affix my signature, in presence of two witnesses.

WOODSON T. MERCHANT.
